UNITED STATES PATENT OFFICE.

JAMES D. O'NEIL, OF JENKINTOWN, PENNSYLVANIA.

BUILDING CONSTRUCTION.

No. 927,273.

Specification of Letters Patent.

Patented July 6, 1909.

Application filed February 10, 1908. Serial No. 415,063.

To all whom it may concern:

Be it known that I, JAMES D. O'NEIL, a citizen of the United States, residing at Jenkintown, county of Montgomery, and State of Pennsylvania, have invented a certain new and useful Improvement in Building Construction, of which the following is a specification.

My invention relates to a new and useful improvement in building construction, and has for its object to provide an exceedingly simple and effective device for constructing a wall for a building of wood and cement.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by letter to the accompanying drawing forming a part of this specification, which is a perspective view of a section of my improvement showing the cement placed therein.

In carrying out my invention as here embodied, A represents studding, which are placed in a vertical position a desired distance apart on necessary sills on the foundation walls. On these studding are placed plates or caps to receive roof timbers, the other necessary joists such as floors are then set in place. These studding have formed on one side a dove tail B, and at a suitable distance from this dove tail on the two sides adjacent to said dove tail are formed the grooves C and C', thus leaving between the said dove tail and the grooves a desired distance of "square", which is equal to the thickness of the boards used in the construction of my improvement. Against this square is placed a strip D, one edge of which is beveled, as indicated at E, so that the bevel edges F of the mold board G will match in order to make it tight for the reception of the cement. To the last named part of the form is pivoted the brace H, at I, the ends of which when in position enter the grooves C and C', and the clamps J and J'. Thus it will be readily seen that a very tight and strong form will be made. A sufficient distance from this part of the form or frame work are placed the studding K in a vertical position at a convenient distance apart, which is usually the same distance as the

studding A, so that they will be able to resist the pressure of the cement. On the inside of these are placed the sheathing boards L, over which is placed an oiled or any suitable water proof paper M, and on this may be nailed strips of wood so as to form fancy designs, or the strips may be nailed on horizontally and vertically so as to form an imitation cement block. The second or outside part of the form is secured to the first part by means of the bolts N, which pass through both sets of studding.

Window and door frames are to be set in their proper places and in such a manner that they will be tight in order that the cement when being placed in the form will be unable to escape. When the frame is in position a liquid cement O is poured in the top thereof until the form is filled, it is then allowed to stand a number of days until it is substantially set, the studding K, the boards L, the mold board G and the strips D are then removed, leaving the cement wall which will be formed about the dove tail B and the studding A standing. The interior of the studding which is left standing with the wall forms a brace for said wall and also a means for lathing and plastering in the regular way, and between the plastering and the cement wall will be formed an air space which makes a cement wall absolutely impervious to heat, cold, moisture and sound.

Having thus fully described my invention, what I claim as new and useful, is

1. A mold for the manufacture of continuous concrete walls comprising a line of studdings, members carried by said studdings for locking engagement with the concrete, means for closing the spaces between said studdings comprising comparatively narrow strips which abut the opposing faces of said studdings and have their free edges beveled, a mold board adapted to fill in between said strips and having beveled edges to engage said beveled edges of said strips and a locking means carried by said mold board and adapted to engage said studding, whereby to lock all of said members together, and a second set of studding and mold boards adapted to form a backing thereto.

2. In a form of the character described, studding having a dove tail formed on one side, and grooves formed in the two adjacent sides set in a vertical position, strips, one edge of each of which is beveled set along the square sides between the dove tail and the

grooves, a mold board, two edges of which are beveled to match with the corresponding bevel on the strips, a brace pivoted to said mold board, clamps also fastened on said mold board, a second set of studding, boards secured thereon and bolts for detachably securing said studding and boards to the rest of the form so that a space will be formed for the reception of a liquid cement.

15 3. A mold for concrete walls comprising studdings having their inner faces provided with dove-tail members for interlocking with the concrete wall, and having their opposing faces provided with grooves; mold boards adapted to approximately fill in between said studdings, filling strips adapted to abut smoothly against said opposing faces and to engage the ends of said mold board, and a lock carried by said mold-board and adapted 20 to engage said grooves in said studdings.

4. A mold for concrete walls comprising

studdings having their inner faces provided with a member which permanently engages the plastic formation, lengthwise grooves formed in opposing faces of said studdings, 25 and a removable molding wall adapted to fill the space between said studdings comprising narrow members adapted to abut said studdings between their inner faces and said grooves and having a beveled face, a 30 mold-board adapted to occupy the space between said narrow members and a locking member pivoted to said mold board and adapted to engage said grooves to lock said molding wall in position.

In testimony whereof, I have hereunto affixed my signature in the presence of two subscribing witnesses.

JAMES D. O'NEIL.
